Primary Examiner — Garth Rademaker*Assistant Examiner* — Jillian Mazzola(74) Attorney, Agent, or Firm — John Rizvi; John Rizvi, P.A.—The Patent Professor®CLAIM

The ornamental design for a clip-on pouch as shown and described.

DESCRIPTION

FIG. 1 is a perspective view of a clip-on pouch showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken line showings of portions of the clip-on pouch form no part of the claimed design.
